UNITED STATES PATENT OFFICE.

JACOB MAURER, OF GENEVA, SWITZERLAND.

PUMP.

SPECIFICATION forming part of Letters Patent No. 716,731, dated December 23, 1902.

Application filed May 12, 1902. Serial No. 106,912. (No model.)

To all whom it may concern:

Be it known that I, JACOB MAURER, manufacturer, of Geneva, Switzerland, have invented certain new and useful Improvements in and Relating to Pumps, of which the following is a specification.

The invention consists of certain new and useful improvements in and relating to that class of pumps in which an explosion of a mixture of hydrocarburet and air is caused to directly expel a certain volume of water or other liquid into a suitable pipe or duct whereby the condensing of the explosive gases which have produced that effect causes in turn a new volume of liquid to be admitted to the pump-chamber.

The improved pump comprises a body or main chamber provided with a suction-pipe and a discharge-pipe and provided with suitable valves, the explosions taking place in the said body or main chamber.

The invention further comprises a device for distributing the explosive mixture and for expelling the products resulting from the explosion, the said device being formed of a cylinder in which a piston is arranged, one face of which is intended to act upon the explosive mixture of gas and air and the other face is intended to expel the said products resulting from the explosion.

During the explosion of the mixture of gas and air and while the water or other liquid is being forced out of the apparatus a volume of steam is produced in the body or main chamber of the pump, and the said steam augments the volume of the residue which is to be expelled. To effect this, the pump is provided with a steam-outlet connecting the body or main chamber in which the explosion takes place with the exterior and which may be shut off by means of a suitable valve. This valve is provided with suitable means for opening the same for an instant directly after the water has been forced out of the pump-body. At that moment the residue of the explosive mixture and the above-mentioned steam contained in the body or main chamber of the pump have a pressure greater than the atmosphere, and the gases escape from the apparatus until the pressure in the body or main chamber has diminished to that of the atmosphere, when the steam-outlet will

be shut automatically by the valve. At this point in the cycle the body or main chamber of the pump is placed into communication with an additional chamber, in which the piston, which is intended to expel the residue, has produced a partial vacuum. A further portion of the gases contained in the body or main chamber is then exhausted from the said body or main chamber into the said additional chamber, and during the next stroke the said piston expels from the apparatus a portion of such exhausted gases.

In the drawings, Figure 1 is a central longitudinal section, and Fig. 2 is a plan view of the apparatus. Fig. 3 is a side elevation of the mechanism acting upon the valve of the steam-valve. Fig. 4 is a side elevation of a portion of the pump, showing the distributor of the mixture of gas and air and the lighting device. Fig. 5 is a section on line 5 5, Fig. 2. Fig. 6 is a horizontal section on line 6 6 of Fig. 5.

In the construction shown, *a* is the body or main chamber of the pump, on the top of which there is arranged an explosion-chamber *b* and which is connected to a suction-pipe *c* and a discharge-pipe *d* and provided with suitable valves *e* and *f*, suction and discharge valves, respectively. The discharge-pipe *d* is connected with an air-chamber *g*, into which extends a pipe *d*², connected to the pipe *d*, and by which the water or other liquid is conveyed to any place where it is to be pumped. 85

To the explosion-chamber *b* is affixed, by means of a suitable support, a cylinder *h* with piston *i*, which is intended to force the explosive mixture into the explosion-chamber and to expel the residue of the explosive mixture 90 out of the apparatus. The piston *i* is actuated by any kind of motor by means of a crank-shaft *k*, carrying a gear-wheel *l*, meshing with a pinion *l*², Fig. 3, which is rotated by the said motor. The wheel *l* is further geared with a wheel *l*³, fixed to a shaft *m* and having suitable cams for actuating certain valves, as will be hereinafter described.

The explosive mixture is stored in a supply-tank 13 and fed to the explosion-chamber 100 by the aforesaid piston in the following manner: During the backward stroke of the piston the latter draws air into the cylinder, and during the forward stroke of the piston the

said air is forced into the explosion-chamber b through a suitable channel, into which a certain quantity of hydrocarburet is injected. To effect this, the top of the cylinder is provided with an air-inlet valve 1, Figs. 2 and 5, allowing the air to enter the said cylinder during the backward stroke of the piston and preventing its escape during the forward stroke of the piston. A channel 10 leads the air which is expelled out of the cylinder into a pipe 11, and the said pipe 11 is provided with suitable wire-gauzes 14, upon which the hydrocarburet from the tank 13 is projected through a tube 12, and the latter is provided with a suitable valve 15 to prevent the air passing from the cylinder into the tube 12. The tube 11 opens above the valve 2, Fig. 5, which is closed during the backward travel of the piston, preventing the residue from the explosive mixture from being sucked back into the cylinder. The said valve is mounted over a portion b' of the igniting-chamber n , placed above the explosion-chamber b . The ignition occurs in the said portion b' of the igniting-chamber, and to prevent the water from coming in contact with the igniting device when the said water is drawn into the body or main chamber of the apparatus the said portion b' of the igniting-chamber is not in direct communication with the interior of the explosion-chamber b , but it is connected with the same by means of a curved channel b^3 . This curved channel b^3 is provided with vertical cross-walls B^{13} , Fig. 1, intended to prevent the water from being projected from the chamber b^3 into the chamber b' .

The igniting device is formed of a box o , Figs. 4 and 5, fixed upon the ignition-chamber and extending into the chamber n' . The bottom of the said box o is provided with an opening o' , which coincides with a corresponding aperture o^2 in a slide or shutter o^3 , fixed to a rocker-shaft o^4 , which has an arm o^5 , acted upon by means of a spring tending to keep the said opening o' closed. The aperture o^2 of the sleeve or shutter o^3 is caused to come in line with the opening o' at the proper time for ignition by means of an arm o^6 fixed to the axis m , so as to act upon the arm o^5 .

The apparatus is provided with any suitable device for effecting the ignition of the explosive mixture. I have shown a gas pipe and burner 16 to project a flame against the bottom of the said box o to cause the ignition of the explosive mixture whenever the openings o' and o^2 coincide. The said flame is also employed to heat the portion of the tube 11 in which the hydrocarburet is to be gasified.

3 is the valve for the escapement of a portion of the residue which remains in the body or main chamber of the apparatus after the expulsion of the water. The said valve 3 is fixed upon the ignition-chamber and is connected with the explosion-chamber b through the chamber b^2 , Fig. 5. As shown in Fig. 3, the opening and closing of the said valve 3 is caused by means of a cam b^3 , fixed to a wheel

b^2 . The opening of the said valve 3 after the expulsion of the water from the body or main chamber of the apparatus is caused by a projection A on the said cam b^3 . Another projection B of the said cam is employed to open the valve 3 during the introduction of the explosive mixture into the explosion-chamber b , so as to allow the latter to expel from the said chamber b a portion of the residue of the previous explosion which may have been brought back approximately to the atmospheric pressure by the water sucked into the body or main chamber after the expulsion of the gases. The recess C of the cam b^3 is employed to keep the valve 3 closed during the explosion, and the space D, where said cam b^3 is discontinued, causes the valve 3 to remain closed during the exhaust of explosive gases, which is caused by the piston i and the suction of water in the body or main chamber. The exhaust which occurs during this last period is effected by a tank p , in which the piston i has first produced a partial vacuum and which at the beginning of this period is placed into communication with the explosion-chamber b by the opening of the valve 4. The opening and closing of this said valve 4 is effected by means of a cam fixed to the shaft m . The channel p' , which connects the tank p to the valve 4, has a branch p^2 , by means of which the said tank is connected to a valve 5, placed on the back of the cylinder. This valve 5 allows the piston to draw into the cylinder a portion of the gases contained in the said tank and to expel the same from the apparatus during the following stroke of the piston through the channel p^3 , which is closed during the suction period by the valve 6.

The working of the apparatus is substantially as follows: Supposing the body or main chamber a of the apparatus to be filled with water and the piston i to be in its extreme backward position, the piston moving forward will force the air contained from the front portion of the cylinder h , and the said air will be carbureted on its passage through the tube 11 and will enter the explosion-chamber b through the valve 2 and the portion b' of the ignition-chamber. During this operation the valve 3 is open and allows the explosive mixture to fill the whole explosion-chamber without compression. While the face of the piston forces the explosive mixture into the explosion-chamber the back face of the same produces a partial vacuum in the tank p , the valve 4 being closed. When the piston i reaches the end of its forward stroke, the valve 3 is closed, and the opening o^2 of the slide or shutter of the igniting device coincides with the opening o' , and the explosive mixture is ignited and the water contained in the body or main chamber a is forced into the discharge-pipe. As soon as this has taken place the valve 3 is opened momentarily, allowing part of the gases remaining from the explosion and the steam to escape from the explosion-chamber b . When the valve 3 has

been closed again, the valve 4 opens and a portion of the gases still remaining in the explosion-chamber is drawn into the tank *p*, and while the portion of the residue passes 5 into the tank *p* the remaining steam is condensed and creates a vacuum in the body or main chamber, which, together with the pressure in the suction-pipe, causes the water or other liquid to rush into the body or main 10 chamber until the same is filled again. During this period of expulsion of the residue of gases and of refilling of the pump the piston *i* has traveled its full return stroke, during which its back face has expelled the gases 15 which it had drawn out of the tank *p* on the previous stroke and its face has drawn into the front portion of the cylinder a volume of air which is intended to be carbureted and pressed into the explosion-chamber, thus 20 completing the cycle.

I claim as my invention—

1. In a pump, the combination with a main chamber, a suction-pipe, a discharge-pipe, a suction-valve and a discharge-valve, of an 25 explosion-chamber connected with and secured to the said main chamber, a cylinder, a piston within said cylinder, means whereby during its travel in one direction the said piston forces an explosive mixture into said 30 explosion-chamber, means for igniting said explosive mixture, means for momentarily exhausting a portion of the gases resulting from the explosion into the atmosphere, a condensing-tank, means for removing the residue 35 due from the explosion-chamber to the said tank, and means for passing the condensed gases through the said cylinder and from the apparatus, substantially as specified.

2. In a pump, the combination with a main 40 chamber, a suction-pipe, a discharge-pipe, an air-chamber connected thereto, a suction-valve and a discharge-valve, of an explosion-chamber connected with and secured to the said main chamber, a cylinder, a piston within 45 said cylinder, means for admitting air to one end of the cylinder during the backward stroke of the piston, a storage-tank for the explosive mixture, a passage from the said tank to the explosion-chamber through which

air is forced by the forward travel of the piston and thereby carbureted before entering the explosion-chamber, means for igniting the explosive mixture, means whereby during the travel in one direction the said piston forces an explosive mixture into said explosion-chamber, means for igniting said explosive mixture, means for momentarily exhausting a portion of the gases resulting from the explosion into the atmosphere, a condensing-tank, means for removing the residue from 60 the explosion-chamber to said tank, and means for passing the condensed gases through the said cylinder and from the apparatus, substantially as specified.

3. In a pump, the combination with a main 65 chamber, a suction-pipe, a discharge-pipe, an air-chamber connected thereto, a suction-valve and a discharge-valve, of an explosion-chamber connected with and secured to the said main chamber, a cylinder adjacent to 70 said explosion-chamber, a piston within said cylinder, a piston-rod, a shaft, a connecting-rod for actuating said piston, means for admitting air to one end of the cylinder during the backward stroke of the piston, a storage-tank for the explosive mixture, a passage from the said tank to the explosion-chamber through which air is forced by the forward travel of the piston and thereby carbureted 75 before entering the explosion-chamber, means 80 for igniting the explosive mixture, a valve between the explosion-chamber and the atmosphere, a valve between the explosion-chamber and said passage from the supply-tank for hydrocarbon, a valve between the 85 explosion-chamber and the said tank, arms secured to said valves, and cams upon the said shaft and adapted to actuate the said arms to operate the said valves to perform 90 the functions of the apparatus, substantially as described.

In testimony that I claim the foregoing as my invention I have signed my name in presence of two subscribing witnesses.

JACOB MAURER.
